Fig. 1

Fig. 2

Fig. 3

FIG. 1 is a side perspective view of a combined music box and clock showing my new design in open position; the side opposite being substantially similar;

FIG. 2 is a top front perspective view thereof in closed position; the rear view being substantially similar; and

FIG. 3 is a front perspective view thereof in open position.

Portions of the ornamentation are shown in detail at the lower right of FIG. 2 and lower left of FIG. 3, it being understood that the ornamentation continues about the perimeter of the design.

The bottom of the combined music box and clock is substantially plain.

I claim:

The ornamental design for a combined music box and clock, substantially as shown and described.
